UNITED STATES PATENT OFFICE.

DAVID R. KNAPP, OF POTTSVILLE, PENNSYLVANIA.

HOISTING MECHANISM.

Application filed May 27, 1920. Serial No. 384,578.

To all whom it may concern:

Be it known that I, DAVID R. KNAPP, a citizen of the United States, and a resident of Pottsville, county of Schuylkill, State 5 of Pennsylvania, have invented certain new and useful Improvements in Hoisting Mechanism, of which the following is a specification.

Some of the objects of the present invention are to provide an apparatus for attaching and releasing a hoisting mechanism to heavy material to be lifted or transported; to provide means operable independently of but in conjunction with a hoisting mechanism 10 for causing a weight to be attached to or released from said hoisting mechanism; to provide an improved tongs for use with hoisting apparatus; to provide means for opening and closing a tongs to engage or release material; to provide an electrically 15 controlled tongs for use with a hoisting mechanism; to provide means for maintaining an operating cable taut; and to provide other improvements as will hereinafter appear.

In the accompanying drawings, Fig. 1 represents a side elevation of a lifting tongs embodying one form of the present invention; Fig. 2 represents an enlarged detail in 20 plan of one form of operating bars used in the tong construction; and Fig. 3 represents a side elevation of the parts shown in Fig. 2.

Referring to the drawings, one form of lifting tongs 10 comprises a pair of arms 35 11 and 12 pivoted at 13 and each consisting of a downwardly curved jaw 14 and an upwardly curved lever 15, the respective pairs of jaws 14 and levers 15 extending in opposite directions and substantially in parallel 40 relation. The tong arms 11 and 12 are of generally heavy material and are suitably fulcrumed to produce the required gripping of the jaws 14, and the weight of the parts, in suspended operative position, is such as to 45 draw and hold the levers 15 together unless opposed by some greater force.

In order to grip the material to be handled, such as an ingot 16 or any other massive weight, the jaws 14 are provided respectively 50 with pointed gripping pins 17, which extend laterally from and in juxtaposed relation upon the jaws 14.

For supporting the tongs 10 and also for raising and lowering them, the levers 15 are 55 respectively provided with openings 20 to

which a bridle 21 of any suitable material is attached and has its upper end fixed to a block 22 in a manner to give an equal pull to the tong levers 15. The block 22 is fixedly secured to the extremities of the hoisting 60 cables 23 which extend upward and are wound upon a hoisting drum 24 of the usual type found on traveling cranes and which is arranged to be operated by a hoisting motor 25 through a suitable gear reduction 65 26 and 27. In the present instance the motor 25 is of the electric type though obviously any other suitable power means may be employed to operate the drum for hoisting operations.

For the purpose of operating the levers 15 to open the jaws 14, a pair of bars 30 and 31 are provided, the bar 30 being pivoted to a pin 32 fixed to the lever 15 of the tong arm 11, and the bar 31 being pivoted to a pin 70 33 fixed to the lever 15 of the tong arm 12. The pins 32 and 33 are respectively located at the same distance from the fulcrum pivot 13 and are normally horizontally opposite each other. The pivoted ends of the respective bars 30 and 31 are preferably bifurcated to straddle the levers 15 and form an effective connection between the parts. The end wall of the bifurcated portion may be beveled, as indicated at 34 to permit free 80 swinging movement, as will be understood. The free ends of the bars 30 and 31 are secured in pivotal relation by a pin 35 and in order to provide for suitable interfitting of the parts the meeting ends of the respective 85 bars 30 and 31 are reduced in width respectively and in right and left hand relation forming overlapping tongues 36 and 37. Thus the two bars 30 and 31 in assembled condition form a sectional link of uniform 90 width throughout its length and well suited to distribute the operating strains and stresses.

As a means for limiting the downward movement of the bars 30 and 31, the bar 30 is provided with an abutment 40 having a face 41 juxtaposed with respect to a similar face 42 on an abutment 43 provided on the bar 31, the angle of these meeting faces 41 and 42 being such as to permit free movement of the bars 30 and 31 within an operative range, but to limit the distance the levers 15 can be drawn together.

As a means to prevent the bars 30 and 31 105 swinging across the line of centers of the 110

22

pins 32 and 33, or above the dotted line position shown in Fig. 1, the bar 30 is provided with angularly disposed abutment face 44 which is located in the path of movement of the tongue 37 to serve as a stop at the predetermined limit of motion, and the bar 31 is similarly provided with a like abutment face 45 in the path of movement of the tongue 36. These two abutment faces 44 and 45 are arranged to be simultaneously engaged by the respective tongues 36 and 37 and thus form a rigid means to prevent further relative movement between the two bars 30 and 31.

15 For controlling the bars 30 and 31 a yoke 46 is secured by the pin 35 and has an eye-bolt 47 or other securing means to which a cable 48 is made fast. The opposite end of the cable 48 is fast to a winding drum 50 and is wound thereon for operation in the usual manner. The drum 50 is fast to a shaft 51 of a motor 52, which is here shown as an electric motor receiving current from the line conductors 53 and 54 leading from a suitable source of current.

30 In order to maintain the cable 48 taut at all times but without placing sufficient tension thereon to overcome the tension of the hoisting cable 23, a relatively high resistance 55 is inserted in series with a lead 56 from one of the conductors, say conductor 54, so that, while current is supplied to the motor 52, the torque of the shaft 51 is insufficient compared to the torque of the drum 24. 35 In consequence, under conditions of lifting or conveying, the motor 52 merely maintains the cable 48 taut, the shaft 51 turning only enough to take up slack.

40 To cause the bars 30 and 31 to move relatively and straighten out, as indicated in dotted lines in Fig. 1, to open the jaws 14 a commutator 60 is provided, the same being of any well known type having contactors and arranged to be manually operated to 45 change its position. In the present instance three electrically connected contactors 61, 62 and 63 are arranged on the movable part of the commutator, the first 61 being positioned to engage a fixed contact 64 in one position 50 of the commutator while the contactor 63 is continuous and engages a second fixed contact 65.

55 The contact 64 is connected by a lead 66 and a low resistance 67 to the conductor 54, while the contact 65 is connected by a lead 68 with the lead 56. Thus when the commutator 60 is turned to bring the contactor 61 into engagement with the contact 64 the resistances 55 and 67 will be in multiple and 60 more current will flow to the motor 52, thereby increasing the torque and causing the tongs 10 to open to release or grip the ingot 16 or other load. The total current is so adjusted that there will be sufficient torque exerted to shift the operating bars 30 and 31

to a position to open the tongs 10, but insufficient to raise them and interfere with the main hoisting mechanism. As long as the commutator 60 is in position to supply this additional current to the motor 52 the 70 tongs 10 will remain open whether they are being raised or lowered by the cable 23.

75 For emergency operation a third contact 70 is connected by a lead 71 and a relatively low resistance 72 to the line conductor 54 75 and the arrangement of the commutator is such that in the emergency position the three resistances 55, 67 and 72 are in parallel with the motor in series and the total resistance is adjusted so that the total current will not 80 be detrimental to the motor 52.

85 The operation of the device takes place as follows:—Assuming the commutator or controller 60 to be in the "off" position, and current on, the circuit through the motor 52 by way of the high resistance 55 will be closed thereby causing the motor 52 to exert a small torque which is sufficient to take up the slack of the cable 48. To open the tongs 10 the controller 60 is turned to close contact 90 between the contactor 61 and contact 64 so that the resistance 67 is thrown into the circuit whereby the motor torque is increased sufficiently to force the levers 15 apart and open the jaws 14. The main drum 24 is now 95 operated to lower the tongs 10 over the ingot 16 or other material, and the control commutator 60 again brought to the "off" position and as the torque of the motor 52 is then insufficient to sustain the weight, the tongs 10 collapse and the pins 17 grip the ingot 16. The material can now be lifted, transported and placed in the desired location where its weight is released from the tongs and the controller or commutator 60 is then thrown 105 again to its first position thereby opening the tongs so that the main hoisting drum 24 can raise the tongs in open position clear of the load which has been released. In case the pins 17 should bind to the material being 110 lifted or moved so that the normal operating torque is insufficient to open the tongs, the controller 60 is thrown to emergency position and allows full current to flow and increase the torque to maximum. 115

120 In lifting tongs as heretofore used, particularly in steel mills where heavy red hot ingots are to be lifted and conveyed from one location to another, it has been necessary to employ a number of operatives to place and secure the hoisting tongs in place upon the ingot or other material. The intense heat is not only detrimental to those required to perform this duty but causes considerable time to be wasted in getting the 125 tongs properly adjusted.

130 By the present invention the tongs can be brought to position by the crane operator and then lowered over the material and automatically gripped for lifting or transport-

ing, thereby releasing the tong setters for other work and saving considerable time as well.

While but one of the many forms in which 5 the present invention may be embodied has been shown and described herein, it is to be understood that the invention is not limited to any specific construction but might be applied to various forms without departing 10 from the spirit of the invention or the scope of the appended claims.

Having thus described my invention, I claim:

1. In a hoisting mechanism, a tongs for 15 gripping an object, a hoisting cable secured to said tongs, means for winding said cable to raise and lower said tongs, means for opening said tongs, means including an electric motor and an operating cable for controlling said opening means, and means for causing said motor to exert a torque less than the weight of said tongs to maintain said operating cable constantly taut.

2. In a hoisting mechanism, a tongs for 25 gripping an object, a hoisting cable secured to said tongs, means for winding said cable to raise and lower said tongs, means for opening said tongs, means including an electric motor and an operating cable for controlling said opening means, means for causing said motor to exert a torque less than the weight of said tongs to maintain said operating cable constantly taut, and means to increase the torque of said motor to actuate 30 said opening means.

3. In a hoisting mechanism, a tongs for 35 gripping an object, operating bars for actuating said tongs, a motor operatively connected to said bars, means to cause said mo-

tor to exert a permanent torque to hold said 40 bars in a predetermined position, and means to increase said torque to cause said bars to operate said tongs.

4. In a hoisting mechanism, a tongs for 45 gripping an object, operating bars for actuating said tongs, a motor operatively connected to said bars, means to cause said motor to exert a permanent torque to hold said bars in a predetermined position, and means to increase said torque "step by step" to 50 cause said bars to operate said tongs.

5. In a hoisting mechanism, a tongs for 55 gripping an object, means for operating said tongs, an electric motor operatively connected to said means and having a constant torque insufficient to cause said means to operate, and means to vary the resistance of said motor to increase the torque at will whereby said operating means is caused to operate.

6. In a hoisting mechanism, the combination of a device for supporting an object to be lifted, operating means for causing said device to engage or release said object, means including an electric motor and an operating 65 cable for controlling said operating means, a current controlling means for constantly subjecting said motor to a torque sufficient to maintain said cable taut without causing said supporting device operating means to 70 function, and a hoisting means operable independently of said device operating means for raising or lowering said supporting device.

Signed at Pottsville, in the county of 75 Schuylkill, State of Penna., this 10th day of May, 1920.

DAVID R. KNAPP.
